(57) **CLAIM**

The ornamental design for a charging case for wireless earbuds, as shown and described.

DESCRIPTION

This application is related to application Ser. No. 29/709,173, entitled Wireless Earbud, and application Ser. No. 29/709,177, entitled Charging Case, both filed on Oct. 11, 2019, the disclosures all of which are incorporated herein by reference.

FIG. 1 is a top, front, right side perspective view of a first embodiment of a charging case for wireless earbuds, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top, front, right side perspective view thereof;

FIG. 9 is a top, front, right side perspective view of a second embodiment of a charging case for wireless earbuds, showing our new design;

FIG. 10 is a front elevation view thereof;

FIG. 11 is a rear elevation view thereof;

FIG. 12 is a left side elevation view thereof;

FIG. 13 is a right side elevation view thereof;

FIG. 14 is a top plan view thereof;

FIG. 15 is a bottom plan view thereof;

FIG. 16 is a top, front, right side perspective view thereof;

(Continued)

FIG. 17 is a top, front, right side perspective view of a third embodiment of a charging case for wireless earbuds, showing our new design;

FIG. 18 is a front elevation view thereof;

FIG. 19 is a rear elevation view thereof;

FIG. 20 is a left side elevation view thereof;

FIG. 21 is a right side elevation view thereof;

FIG. 22 is a top plan view thereof;

FIG. 23 is a bottom plan view thereof; and,

FIG. 24 is a top, front, right side perspective view thereof.

The broken lines in the drawings depict portions of the charging case for wireless earbuds that form no part of the claimed design. The portions shown in a pattern of stipple illustrate areas of contrasting appearance.
